UNITED STATES PATENT OFFICE.

BENJAMIN W. BALDWIN, OF PITTSBURG, PENNSYLVANIA.

JOURNAL-BOX.

SPECIFICATION forming part of Letters Patent No. 283,950, dated August 28, 1883.

Application filed April 13, 1883. (Model.)

To all whom it may concern:

Be it known that I, B. W. BALDWIN, a citizen of the United States, residing at Pittsburg, in the county of Allegheny and State of Pennsylvania, have invented certain new and useful Improvements in Journal-Boxes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in the construction of journal boxes or bearings for railroad-cars, locomotives, and for other purposes.

20 The object of my invention is to provide a safe and reliable journal box or bearing which will insure protection of life, limb, and property where such are dependent upon the journal-boxes and journals being kept cool; and to this end my invention consists in forming 25 the boxes or bearings hollow, or with a cavity therein for the reception of the lubricant, and providing them with filling and vent orifices, which also serve to allow the oil, when expanded by the heating of the box or bearing, 30 to flow over the ends of the boxes and onto the axle, as will more fully appear.

35 My invention consists, further, in casting the bearings or boxes with a cavity therein and therethrough in the direction of their length, then closing the ends of the cavity by means of metal fillets and soldering the same securely therein.

40 Referring to the drawings, Figure 1 is a top or plan view. Fig. 2 is an end view. Fig. 3 is a sectional top view on the line $\alpha\alpha$ of Fig. 4. Fig. 4 is a sectional end view on the line yy of Fig. 3. Fig. 5 is a view in perspective of one of the fillets which are placed in the ends of the cavity to close the same.

45 A designates the upper or bearing box as ordinarily used in supporting the bodies of railway cars or locomotives upon the journals or axles of the trucks. The box A is by preference cast in one piece, with a cavity, B, extending therethrough in the direction of the length of the box, the upper and lower shells being connected or strengthened at intervals

55 by means of the studs or stanchions a . I may, however, without departing from the spirit of my invention, cast the upper shell and the studs or stanchions a in one piece of an inferior or common metal, and for the lower shell or bearing-surface insert, in any well-known or convenient manner, Babbitt metal, or metal of a superior quality from that of the upper 60 section or shell. I prefer, however, to cast the boxes or bearings in one piece, with the cavity B extending therethrough, and the strengthening studs or stanchions a connecting at various points the inner and outer or 65 upper and lower shells.

C are fillets or pieces of metal for closing the ends of the cavity B, and forming within the body of the bearing or box a liquid-holding compartment. The fillets C are soldered, 70 brazed, or otherwise secured in the cavity, so as to make a tight joint.

b is a filling-orifice, through which oil or other lubricant is poured into the cavity B, and c is a vent-hole, through which the air 75 escapes when the oil is being poured into the filling-orifice b, so that the cavity B can be readily and rapidly filled entirely full of oil or other lubricating material.

b' and c' are grooves leading from the filling 80 and vent holes b and c down to the ends of the boxes, which allows the oil to flow down onto the axle or spindle when the boxes have become heated to such an extent as to expand the oil, and in this way the bearing becomes 85 lubricated at the proper time to prevent accident from the overheating of the box.

The general contour of my journal-box does not differ in an essential manner from other boxes now in the market, and is provided with 90 the necessary projecting flanges, by which it is held in its proper position in the frame-work. The boxes may also be provided with an oil-channel leading direct to the spindle or axle, so that oil can be applied direct to the axle, as 95 is now the custom, the main feature of my invention being the magazine or cavity in which the oil is stored, and which is brought into requisition by the heating of the box and the expansion of the oil at the time the oil is 100 most needed to lubricate the axle.

My invention is specially adapted for the journal-bearings or axles of cars, locomotives, and rolling vehicles generally; but I do not

limit myself to such, as it is obvious that it can be adapted for use wherever a journal-bearing is liable to become heated.

I am aware that journal-boxes provided with 5 a cavity for the reception of a lubricant is not broadly new, such cavities being connected with the bearing or wearing surface of the box by means of channels or ducts.

I am also aware that journal-boxes have been 10 made hollow for the holding of a cooling-liquid, and such I do not claim.

Having thus described my invention, what I claim, and desire to secure by Letters Patent, is—

15 1. The method herein described of lubricating journals and axles, the same consisting in placing within a hollow journal-box the proper lubricant, which is forced out of apertures substantially such as described by the 20 expansion of the lubricant, superinduced by

heat from the axle or spindle, to lubricate the same.

2. A self-lubricating journal-box cast with a central longitudinal cavity, B, extending through its entire length, in combination with 25 the fillets C C and strengthening-studs *a*, as and for the purpose set forth.

3. A journal-box having a central cavity, B, for the reception of the lubricating material, in combination with the filling and vent ori- 30 fices *b* and *c*, provided with the grooves or ducts leading therefrom to the ends of the journal-box, as and for the purpose set forth.

In testimony whereof I affix my signature in presence of two witnesses.

BENJ. W. BALDWIN.
